UNITED STATES PATENT OFFICE.

BERNARD J. McCABE, OF DETROIT, MICHIGAN.

AUTOMATIC FOLDING UMBRELLA.

1,063,989.

Specification of Letters Patent. Patented June 10, 1913.

Application filed December 18, 1911. Serial No. 666,405.

To all whom it may concern:

Be it known that I, BERNARD J. McCABE, citizen of the United States, residing at Detroit, in the county of Wayne and State of Michigan, have invented certain new and useful Improvements in Automatic Folding Umbrellas, of which the following is a specification.

This invention comprehends certain new and useful improvements in folding or collapsible umbrellas of the telescoping stick type, and the invention has for one of its main objects a simple and efficient construction of device of this character which will be automatic in the operation of both opening and closing the umbrella ribs.

The invention also has for its object an umbrella of this character, the parts of which are so constructed and arranged relatively to each other that the umbrella in closed position may occupy a minimum amount of space so that it may be conveniently carried in a hand bag or the like, and easily extended to operative condition when desired for use.

The invention also has for its object a folding or collapsible umbrella which will be strong and durable and well able to withstand hard usage, and particularly the wind stresses to which umbrellas are so frequently subjected, the parts being so arranged that the umbrella may turn "inside out" and subsequently resume its normal shape without undue straining of or injury to the ribs, stretchers or spreaders and their concomitant parts.

A further object of the invention is to provide an umbrella of this type with a sheath or casing so connected thereto that when the telescoping sections of the rod or stick are extended, the said casing will be automatically drawn up into the handle section so that it may always be at hand when required, the casing being automatically exposed when the rod or stick is in collapsed condition so that the sheath may be slipped over the closed and collapsed umbrella, to protect the cover and other parts. And the invention also aims to generally improve this class of devices and to render them more useful and commercially desirable.

With these and other objects in view, as will more fully appear as the description proceeds, the invention consists in certain

constructions, arrangements and combinations of the parts that I shall hereinafter fully describe and claim.

For a full understanding of the invention, reference is to be had to the following description and accompanying drawing, in which:

Figures 1, 2, 3 and 4 are longitudinal sectional views of my improved umbrella; Figs. 5, 6 and 7 are views of the rib structure, as are Figs. 8, 9 and 10; Fig. 11 is a longitudinal sectional view of the intermediate portion of the stick; Fig. 12 is a sectional side elevation of another portion of the stick continued up from Fig. 11; Fig. 13 is a fragmentary sectional view of the plunger tip section of the stick; Fig. 14 is a sectional side elevation of a portion of the stick; Fig. 15 is a transverse sectional view on the line 15—15 of Fig. 11; and Fig. 16 is a sectional view showing the parts viewed at right angles to the showing in Fig. 2.

Corresponding and like parts are referred to in the following description and indicated in all the views of the drawing by the same reference characters.

The stick or rod A of my improved umbrella includes in the present embodiment of the invention, tip sections 1 and 2, the tip section 1 possessing the function of a plunger as will be hereinafter more specifically described, and telescoping within the tip section 2. The rod also includes a runner section 3 telescoping on the tip section 2, an intermediate section 4 which telescopes over the enlarged lower end 2^a of the tip section 2, and a handle section 5 which telescopes over the intermediate section 4. All of these sections are tubular, as clearly illustrated in the drawings, and preferably the handle section 5 is incased in veneer, as indicated at 6, said veneer being ornamented in any desired way and possessing any desired configuration, as taste or judgment may dictate.

The tip section 1 is provided at its outer end with a plug or ferrule 7 and is formed intermediate of its ends with diametrically opposed longitudinal slots 8 accommodating the ends of a transversely extending pin 9 which is secured to the tip section 2 intermediate of the ends of the latter. A closing spring 10 is housed within the section 1 and is secured at its upper end to the pin 9, the lower end of said spring being secured to a

corresponding pin 11 which is fastened in the lower end of the runner 3. The transversely extending pin 11 is accommodated not only by the slots 8 of the tip section 1, 5 but by the corresponding and registering slots 12 that are formed in the tip section 2.

13, designates the opening spring of the device. This spring is mounted within the tip section 1 and is secured at its upper end 10 to the pin 11, the lower end of said spring being secured to a transverse pin 14 fastened in the lower end of said tip section 1. Each of the springs 10 and 13 is contractile, and their correlated actions or operations will 15 be hereinafter specifically described, it being borne in mind, however, that the opening spring 13, when under tension, is relatively and preferably stronger than the closing spring 10 in order that it may perform 20 the double function of opening the umbrella and setting the umbrella closing mechanism.

The notched crown, 15, is secured in any desired way to the upper end of the tip section 2, as by the registering beads 16 25 formed while attaching the crown number to the tubular tip section. The ribs that are pivotally connected at their inner ends to the crown 15 are designated B as a whole, each of said ribs embodying an upper section 17 of channel metal, as shown, and a lower section 18 which is preferably formed of round wire of suitable strength and size. The runner is provided with a flexing 30 stretcher or spreader 19 which is pivotally connected at one end to the end of the runner 3 and which is also formed of channel metal adapted to nest within the section 17 of the rib, the other end of the stretcher being welded or otherwise fixedly connected 35 to the outer end of the upper section 17 within a sleeve 20. The lower section 18 of each rib passes through the sleeve 20 for a sliding movement within the nested stretcher and upper section of the rib, the 40 inner end of the section 18 being flattened and returned upon itself around the outer side of the sleeve 20 to form a spring latch 21 designed to engage the said sleeve to hold the outer section in extended relation to the inner section. Each latch 21 is preferably 45 provided with a curved releasing finger 22 at its free end, designed for engagement by a releasing cup 23 formed on the upper end of the handle section 5, it being at this 50 point understood that when the ribs are folded upon the rod or stick A and the handle section 5 is pushed over the adjoining sections of the rod, the cup 23 will wedge around the circle of releasing fingers 55 22 and release the latches 21 from the sleeves 20, a continued movement of said section 5 serving to force the sections 18 upwardly 60 into the nested stretchers 19 and corresponding rib sections 17, so as to collapse the ribs.

65 The cover of the umbrella it not shown,

the same being preferably omitted for the sake of clearness; but it is to be understood that the cover is stitched to the eyes 24 formed in the ribs near the tip ends of the latter and also stitched by sewing to notches 70 25 that are formed in the latches 21 contiguous to thimbles 26 that are carried by the sections 18 at the inner or upper ends of the latter, and that have an easy sliding fit over the outside of the upper rib sections 17. 75

The casing or sheathing 27 of my improved umbrella may be of any desired construction or design, and is preferably provided at one end with a hook 28 by which it is swung from and permanently connected to a transversely extending pin 29 secured in the lower end of the intermediate section 4, whereby when the parts are collapsed, as illustrated in Fig. 1, the casing will be exposed and may be easily slipped 80 over the folded umbrella. When the parts of the stock or rod are extended, it is evident that the casing 27 will be drawn upwardly within the handle section 5 where it will be out of the way but always at hand 85 and not liable to be lost, so that it may be used whenever desired or necessary.

From as much of the description as has preceded in connection with the correlated views of the accompanying drawing, the operation of collapsing the umbrella after it has been closed will be apparent, the tubes sliding one upon the other in an evident manner, and the rib unlocking and the collapsing cup 23 carried by the handle section 100 5 unlocking the latches 21 and moving the sections 18 into the nested spreaders 19 and corresponding rib sections 17. The closed position of the parts is illustrated in Fig. 1. The parts are held in this collapsed condition with the opening spring 13 extended and held under tension by the engagement 105 of the catch 34—35 with the catch 36—37. To extend the rod or stick A, it is only necessary to pull the various sections outwardly relatively to each other, with the exception of the top section 1, to the position illustrated in Fig. 3, which will result in still holding the spring 13 tense, and will also result in drawing the casing 27 up into 110 the handle section 5. The handle section will be automatically locked in extended relation to the intermediate section 4 by means of a spring latch 30 carried by the lower end of the intermediate section 4, snapping 115 out into a slot 31 formed in the said handle section. The section 2 will be held in extended relation to the intermediate section 4 by means of a spring latch 32 carried by the enlarged lower end 2^a of the section 2 snapping 120 out into a slot 33 formed in the intermediate section 4 near the upper end of the latter. I shall now describe the means for 125 and operation of automatically opening and closing the umbrella. 130

As best seen in Fig. 13, the opening spring 13 is returned upon itself at its lower end where it is connected to the pin 14 and bent to form a catch 34 formed with a shoulder 35 designed to pass and be caught by the shoulder 36 of a spring latch 37 carried by the enlarged lower end 2^a of the section 2. The enlarged lower end of the section 2 also carries a spring latch 38 formed with a shoulder 39 designed to be engaged by a bar 40 formed on and extending longitudinally downward from the lower end of the runner section 3, as best illustrated in Fig. 12. The spring latches 36 and 39 are preferably formed of square steel, and have inwardly turned and inclined free ends 41 between which a runner bar 42 is interposed, said runner bar working in a longitudinal groove 43 formed in the enlarged lower end 2^a of the top section 2 and engaging with the catch 39 and held thereby. Said end is also formed with a longitudinal groove 44, for the runner bar 40. The lower end of the release bar 42 is connected to a spring controlled handle or button 45 carried by the same spring 46 to which the latch 30, before mentioned, is connected, preferably integrally.

In the operation of opening the umbrella, downward pressure on the button or handle 45 which projects out through a slot 46' formed in the handle section 5 and against the resistance of the spring 46, will move the bar 42 far enough to disengage the releasing bar 42 from the latch 38 and the latter will be disengaged from the runner bar 40, permitting the spring 13 to contract so as to draw the runner 3 downwardly and thereby flex the spreaders 19 and automatically cause the ribs to open, so as to assume the position illustrated in Fig. 4.

It is to be understood that enough tension remains in the spring 13 to keep the cover well stretched through the stretching action of the spreaders or stretchers 19. It will be noted that by this initial or preliminary movement of the spring 13 the closing spring 10 will be expanded somewhat while the umbrella opens, this being due to the fact that the spring 13 is much stronger than spring 10 in order, as before stated, that it may perform the double function of opening the umbrella and setting the closing mechanism. Hence, a further downward movement of the bar 42 by pressure upon the button or handle 45 which opens the umbrella, will release the bar 42 from the latch 37, and the latter will become disengaged from the shoulder 35 of the catch 34 which is formed as a continuation of the spring 13. The tip section 1, to which the spring 10 is connected, is released by this action, and said tip section is then extended to the position illustrated in Fig. 2, by spring 10, carrying the runner with it and closing the umbrella.

After closing, should it be desired to open the umbrella again, it is only necessary to press the tip section 1 back into the tip section 2 until it again locks (as shown in Fig. 3,) thus putting the opening spring 13 under tension again, so that pressure upon the release button or handle 45 will again bring runner 3 down and open the umbrella as before. To telescope the umbrella, it is first closed by the operation just described, the top section 1 is then pushed inwardly, and the handle section 5 is telescoped over the intermediate section 4. Further pressure upon the handle section 5 telescopes such section and the intermediate section 4 over the tip section 2, and when the upper end of the handle section 5 reaches the meeting point of the ribs, the releasing cup 23 will catch underneath the spring latches 21, thereby unlocking the lower sections 18 of the ribs and carrying all up together until the umbrella is fully telescoped, as in Fig. 1. The casing 27 which, while the umbrella was extended, remains within the handle, as illustrated in Fig. 3, can now be drawn over the outside and tied, and the umbrella is ready to be placed in a suit case, hand bag, or other receptacle, where it will occupy a minimum amount of space.

In order to safeguard the umbrella against damage by wind, which is one of the objects of my invention as set forth at the outset of the specification, the runner section 3 is provided at its upper end with a series of laterally spaced longitudinally extending fingers 3^a, to which the inner ends of the spreaders 19 are directly pivotally connected. Hence, it will be understood by reference to Fig. 12, particularly, that the umbrella can be turned completely wrong side out, owing to the yielding of the fingers 3^a, and will then automatically return to its normal shape, due to the pull exerted by the spring 13, without any injury to the parts.

While the foregoing description in connection with the accompanying drawings illustrates what I believe to be the preferred embodiment of my invention, it is to be understood that the invention is not limited thereto, but that various changes may be made in the construction, arrangement and proportions of the parts without departing from the scope of the invention as defined in the appended claims.

Having thus described my invention, what is claimed is:

1. An umbrella, including a tubular stick, opening and closing springs mounted in said stick, a runner to which said springs are connected, ribs, spreaders connected to said ribs and to the runner, a plunger tip section carrying said springs, means for holding the opening spring under tension, means for releasing said holding means whereby to permit said spring to act to move the runner

- in a direction to open the ribs, and means for releasing the plunger, whereby to permit the other spring to act to close the ribs.
2. An umbrella, including a tubular stick, 5 ribs pivotally connected thereto, spreaders connected to the ribs, a runner mounted on said stick and connected to the spreaders, a plunger tip section, opening and closing springs carried thereby, means for holding 10 the plunger tip section retracted in the stick with the opening spring under tension, the opening spring being stronger than the closing spring and both springs connected to the runner, means for releasing the opening 15 spring so as to draw the runner down on the stick and place the closing spring under tension, and means for subsequently releasing the tip section so as to permit the closing springs to act to move the section outwardly and also move the runner in a direction to close the ribs.
3. An umbrella, including a tubular stick embodying an extensible plunger tip, opening and closing springs housed in said tip, 20 means for holding said tip retracted in the stick with the opening spring under tension, a runner mounted on the stick and connected to both springs, ribs pivotally connected to the stick, spreaders connected to the ribs 25 and to the runner, and means initially movable to release the opening spring to permit the same to contract and subsequently movable to release the plunger section so as to permit the closing spring to act.
- 35 4. An umbrella, including a tubular stick, a plunger tip section embodied therein, opening and closing contractile springs housed in said plunger tip section in longitudinal alinement with each other, the outer 40 end of the closing spring being secured to the stick and the lower end of the opening spring being secured to the plunger tip, ribs pivotally connected to the stick, spreaders connected to the ribs, a runner mounted 45 on the stick and connected to the spreaders, the adjoining ends of said springs being connected to the runner, means for holding the opening spring extended and the plunger tip retracted in the stick, and means for releasing said holding means to permit the opening spring to contract and for subsequently releasing the plunger tip to permit the closing spring to act and extend the plunger tip from the stick, for the purpose 50 specified.
5. An umbrella, including a tubular stick embodying a plunger tip section, opening and closing springs housed within said section, ribs pivotally connected to the stick, spreaders connected to said ribs, a runner 55 movable on the stick and connected to said springs and to the spreaders, the runner being provided with a bar, the plunger tip being provided with a catch, latches carried by the stick and automatically movable into engagement with said bar and catch to hold the opening spring extended under tension and the plunger tip retracted in the stick, and means for releasing said latches, for the purpose specified. 70
6. An umbrella, including a tubular stick embodying a plunger tip section, opening and closing springs housed within said section, ribs pivotally connected to the stick, spreaders connected to said ribs, a runner 75 movable on the stick and connected to said springs and to the spreaders, the runner being provided with a bar, the plunger tip being provided with a catch, latches carried by the stick and automatically movable into engagement with said bar and catch to hold the opening spring extended under tension and the plunger tip retracted in the stick, and means for releasing said latches including a releasing bar carried by the 80 stick and movable into engagement with said latches to release the latter.
7. An umbrella, including a sectional tubular stick, embodying a plunger tip section, opening and closing springs within 90 said tip section, ribs pivotally connected to the stick, spreaders connected to the ribs, a runner movable on the stick and connected to both of said springs, the runner being provided with a bar and the plunger tip 95 being provided with a catch, latches carried by one of the sections of the stick and automatically engageable with said bar and catch to hold the opening spring extended under tension and the plunger tip retracted 100 in the stick, and a releasing bar carried by another section of the stick and movable into engagement with said latches, for the purpose specified.

In testimony whereof I affix my signature 105
in presence of two witnesses.
